UNITED STATES PATENT OFFICE

160,104

TORCH

John G. Mason, Anderson, Ind.

Application February 9, 1949, Serial No. 762

Term of patent 3½ years

(Cl. D48—24)

To all whom it may concern:

Be it known that I, John G. Mason, a citizen of the United States of America, residing at Anderson, in the county of Madison and State of Indiana, have invented a new, original, and ornamental Design for a Torch, of which the following is a specification, reference being had to the accompanying drawing, forming part hereof, in which:

Fig. 1 is a side elevational view of a torch, showing my new design.

Fig. 2 is a front view thereof, and

Fig. 3 is a top plan view thereof.

I claim:

The ornamental design for a torch, substantially as shown.

JOHN G. MASON.
